GARMENT SLEEVE STEAMER AND
STRETCHERCarl E. Lendle, Youngstown, Ohio, assignor to
United States Hoffman Machinery Corporation,
New York, N. Y., a corporation of Delaware

Application August 23, 1944, Serial No. 550,698

5 Claims. (Cl. 223—73)

1

This invention relates to the renovation of garments and has among its objects and advantages the provision of an improved sleeve renovating and stretching device.

In the accompanying drawings:

Figure 1 is a side elevational view partly in section of a machine embodying my invention;

Figure 2 is a top plan view;

Figure 3 is a view of one of the sleeve clamps;

Figure 4 is a similar view illustrating the clamp in its sleeve clamping position; and

Figure 5 is a view of a drying air deflector means.

In the embodiment selected for illustration, I make use of a base 10 on which is mounted a housing 12. To the housing 12 is fixedly secured two elbow or sleeve supports 14. The supports 14 are identical in construction and are spaced in parallel relationship, the spacing being such as to facilitate the positioning of a sleeve upon each support without interference from the other. Underneath the two supports 14 are positioned two front sleeve supports 16. Each support 16 lies in a common vertical plane with one of the supports 14. While the two supports 14 are fixedly mounted, the two supports 16 are mounted for movement toward and away from their respective supports 14, so that sleeves mounted on the supports may be stretched transversely for forming purposes.

A U-shaped member 18 has its legs 20 pivotally connected at 22 with a support 24. Each leg 20 is pivotally connected at 26 with one of the supports 16 intermediate the ends of the latter, and each leg extends freely through a slot 28 in the housing 12.

A shaft 30 extends transversely of the housing 12 and is rotatably journaled in bearings 32 secured to the housing. To the shaft 30 is secured a lever 34 having a bifurcated end 36 slidably engaging and guiding the bight 38 of the member 18. To the end 36 is connected one end of a tension spring 40 having its other end anchored to the housing 12.

The lever 34 is urged clockwise by the spring 40, which clockwise rotation pivots the member 18 for moving the supports 16 toward their respective supports 14. A quadrant 42 coacts with the pawl 44 on the lever 34 for latching the lever against rotation by the spring 40. Stretching pressure is applied to the sleeves by pivoting the lever 34 in a counter-clockwise direction. Since the operator usually stands at or about the ends of the supports 14 remote from the housing 12, it is a relatively easy matter to exert a pull on the

2

lever 34 for applying forming pressure to the supports 16. Mere lifting of the pawl 44 permits the spring 40 to pivot the lever 34 to move the supports 16 to sleeve releasing positions.

5 Slidably mounted on each of the supports 14 is a sleeve pad 46 inserted in the outer end of the sleeve as it is placed in position on one of the supports 14 and its coating support 16.

In Figures 3 and 4, a sleeve clamp 48 is illustrated in association with its respective pad 46. Both sets of pads 46 and their respective clamps 48 are identical in construction so that the description of one will apply to both.

The clamp 48 comprises two padded members 50 and 52 paralleling the padded plate-like members 54 of the pad 46. Member 52 is fixedly secured at 56 to bars 58 extending loosely through a plate 60 pivotally mounted at 62 on a lug 64 on the pad 46. Member 50 is slidably mounted on the bars 58. Compression springs 66 are mounted on the bars 58 and interposed between the respective members 50 and 52 and the plate 60. A shaft 68 extends loosely through a sleeve 70 on the plate 60 and through openings in the members 50 and 52. A wing nut 72 is threaded on the shaft 68 and engages a boss 74 on the member 50. Shaft 68 extends loosely through the boss 74.

To the end of the shaft 68 opposite the wing nut 72 is connected an eccentric 76, as at 78. A lever 80 is attached to the eccentric 76 to facilitate rotation thereof. The eccentric 76 engages the member 52 and guidingly engages plates 82 attached to the member 52. While the eccentric 76 pivots freely between the plates 82, the plates have engagement with the eccentric so that the clamp 48 may be rotated about the axis of the shaft 68.

Figures 1 and 3 illustrate the normal position 40 of the clamp 48, at which time the clamp is so positioned as to permit the sleeve to be slipped easily over the pad 46. As the clamp 48 is pivoted downwardly to the position of Figure 4, the sleeve may be firmly clamped in position against the pad 46, as at 84, through rotation of the eccentric 76 about its axis 78. With the lever 80 in its dotted line position of Figure 4, the members 50 and 52 are urged to the positions of Figure 3 by reason of the springs 58.

50 In Figure 2, a bar 86 fixedly interconnects the two pads 46, which bar is pivotally connected with rods 88 pivotally connected with arms 90 attached to a shaft 92 rotated through the medium of a lever 94. Thus rotation of the lever 94 imparts sliding motion to the pads 46 on the sup-

ports 14. Since the clamps 48 are carried by the pads 46, the clamps shift with their respective pads 46.

The lever 94 is provided with a pawl 96 coacting with a quadrant 98 so that the pads 46 may be secured in the desired positions. Curved shoulder-engaging members 100 are attached to the outer ends of the supports 14 for engagement with the shoulder portion of the garment. U-shaped clamps may be pressed over the shoulder portion of the garment for securing the sleeve against relative shifting when a pull is exerted thereon by one of the clamps 48. Such a U-shaped clamp is illustrated at 102 in Figure 2 in association with one of the supports 14.

Each support 14 is provided with a steam pipe for admitting steam inside the sleeve. Figure 1 illustrates a pipe 104 bent back upon itself at 106 adjacent the shoulder-engaging member 100. The upper run 108 of the pipe is perforated and lies closely adjacent the lower edge of the support 14. The run 108 enters the support 14 at 110 and connects with a quick opening valve 112. Both supports 14 are of tubular formation. Pipe 104 has a return run 114 for condensate which may form therein. Both supports 14 are provided with identical steam pipes.

Both runs 108 connect with the valve 112 and the latter is in communication with a chamber 115 provided with a steam inlet pipe 116 leading to a suitable steam generator (not shown). An outlet pipe 118 has communication with the bottom of the chamber 115 for the removal of condensate which may form therein. Thus steam only flows through the steam pipes. Valve 112 may be actuated by a foot-operated lever 120.

Inside the housing 12 is mounted a fan 122 driven by a motor 124. The fan 122 is positioned inside an open-ended tube 126 having one end secured to the housing axially of an opening 128 therein. A steam heated coil 130 is mounted inside the tube 126 between the fan and the outlet end of the tube. Heated air blown by the fan 122 is deflected upwardly through a neck 132 provided with deflecting vanes 134. Neck 132 is located underneath the supporting arms 14 and 16 so as to deflect heated air upwardly about the sleeves mounted on the supports.

The supports 16 are perforated at 136 for the passage of steam released inside the sleeves by the steam pipe 104.

In operation, one or two sleeves may be handled at a time. As a rule, both sleeves are mounted on the respective supports 14 and 16. With the sleeves positioned on the supports, the clamps 48 are pivoted downwardly for firmly securing the outer ends of the sleeves. Graduations 138 are provided on the supports 14 for locating the pads 46 in conformity with sleeves of predetermined lengths. Thus the sleeves may be held tautly in a lengthwise direction, in addition to appropriately stretched with respect to width and contour. The supports 14 and 16 stretch the sleeve crosswise for forming purposes, and the supports eliminate folds in the lining of sleeves so that the processed sleeve will take a smooth appearance devoid of seam and wrinkle marks incident to pressing by conventional pressure devices.

With the sleeves stretched with respect to length and width, steam is admitted to the sleeves by opening the valve 112. After steaming, the sleeves are quickly dried through the circulation of heated air about the sleeves.

A table 140 is mounted on the housing 12 un-

derneath the supports 16 which table serves as a support for the body of the garment during the steaming process.

The machine may be successfully operated by inexperienced operators. A machine of this type produces a smooth, neat piece of work. It eliminates soiled creases in the sleeves after the sleeve hems are let out, eliminates crooked sleeve openings, and one sleeve only may be lengthened without showing any difference in appearance from the other sleeve. By merely stretching the sleeve, the machine brings out the nap of the material without showing the impressions of the undersleeve seam and the like.

Without further elaboration, the foregoing will so fully illustrate my invention, that others may, by applying current knowledge, readily adapt the same for use under various conditions of service.

I claim:

1. A garment sleeve steamer and stretcher comprising first and second supports for inside sleeve engagement, said second support being movable, means for moving said second support relatively to said first support to stretch the sleeve crosswise, a garment shoulder engaging end on said first support, a sleeve clamp slidably longitudinally of said first support for the other end of said sleeve coacting with said garment shoulder engaging end for stretching the sleeve lengthwise, and means for admitting steam inside the sleeve.

2. A garment sleeve steamer and stretcher comprising first and second supports for inside sleeve engagement, said second support being movable, means for moving said second support relatively to said first support to stretch the sleeve crosswise, a garment shoulder engaging end on said first support, a sleeve clamp slidably longitudinally of said first support for the other end of said sleeve coacting with said garment shoulder engaging end for stretching the sleeve lengthwise, said sleeve clamp comprising a pad, and padded members coacting with said pad to clamp the sleeve, said padded members being pivotally mounted on said pad and the latter being slidably on said first support.

3. A garment sleeve steamer and stretcher comprising a pair of sleeve supporting devices respectively insertable in the sleeves of the garment, each of said devices comprising first and second members for inside sleeve engagement, said second members being movable relatively to their respective first members, means for moving said second members to stretch the sleeves crosswise, means for admitting steam inside the sleeves, said first members being provided with garment shoulder engaging ends, and sleeve clamps slidably longitudinally of said first members for the other ends of the sleeves coacting with said garment shoulder engaging ends for stretching the sleeves lengthwise.

4. A garment sleeve steamer and stretcher comprising a pair of sleeve supporting devices respectively insertable in the sleeves of the garment, each of said devices comprising first and second members for inside sleeve engagement, said second members being movable relatively to their respective first members, means for moving said second members to stretch the sleeves crosswise, means for admitting steam inside the sleeves, said first members being provided with garment shoulder engaging ends, sleeve clamps slidably longitudinally of said first members for the other ends of the sleeves coacting with said garment shoulder engaging ends for stretching the sleeves lengthwise.

the sleeves lengthwise, said sleeve clamps each comprising a pad slidable on its respective first member, said pads being fixedly connected one with the other for unit sliding movement, and padded members pivotally connected with their respective pads.

5. A garment sleeve steamer and stretcher comprising a pair of sleeve supporting devices respectively insertable in the sleeves of the garment, each of said devices comprising first and second members for inside sleeve engagement, said second members being movable relatively to their respective first members, means for moving said second members to stretch the sleeves crosswise, means for admitting steam inside the sleeves, said first members being provided with garment shoulder engaging ends, sleeve clamps slidable longitudinally of said first members for the other ends of the sleeves coacting with said garment shoulder engaging ends for stretching the sleeves lengthwise, said sleeve clamps each comprising a pad slidable on its respective first member, said pads being fixedly connected one with the other for unit sliding movement, padded

members pivotally connected with the respective pads, spring means acting on the padded members for maintaining a predetermined spacing therebetween greater than the thicknesses of their respective pads to pivot freely into overlapping relationship therewith, and eccentrics provided with handles for moving the padded members into pressure engagement with their respective pads, said handles being arranged to constitute handle means for pivoting the padded members relatively to their respective pads.
